UNITED STATES PATENT OFFICE.

RALPH D. WHITMORE, OF GALVA, ILLINOIS.

GRAIN-SPOUT.

1,288,334.

Specification of Letters Patent. Patented Dec. 17, 1918.

Application filed May 25, 1917. Serial No. 170,869.

To all whom it may concern:

Be it known that I, RALPH D. WHITMORE, a citizen of the United States, residing at Galva, in the county of Henry and State of Illinois, have invented certain new and useful Improvements in Grain-Spouts; and I do hereby declare that the following is a full, clear, and exact description of the invention, which will enable others skilled in the art to which it appertains to make and use the same.

This invention relates to improvements in spouts and more particularly to a spout of a tapered or conical form used for conveying grain and the like.

An object of the present invention is to provide a certain desired manner of securing a removable or renewable bottom of a spout section in position where it will be firmly and permanently held until necessary to remove it.

Another object of the invention is to furnish a spout section having a removable portion upon which the grain or other material is conveyed, providing one of the parts of the structure with a notch, and the removable portion with a stud to engage it which will properly center such portion and prevent its lateral movement as well as to provide means for permanently securing the portion in place until its removal is required.

To the end that my invention may be understood, I have provided the accompanying drawing, showing the preferred form of my device, which, however, is susceptible of changes that will lie within the meaning and intent of the invention and within the scope of the accompanying claims.

Figure 1 shows the under side of a spout and a removable bottom partially entered into said spout.

Fig. 2 is a cross section of the spout on line $x-x$, Fig. 1.

Fig. 3 is a longitudinal section of parts of the structure, showing a bolt for securing the portions together.

Fig. 4 is a longitudinal section of portions of the spout on line $y-y$, Fig. 1; and,

Fig. 5 shows, in perspective, the portions shown in Fig. 4.

A indicates a spout section of tapered form opened at both ends. It is provided

with a longitudinal opening B closed by a tapered insertible portion C, the small end of the section being provided with a notch 55 D lying longitudinally of the section communicating with the opening B.

On the small end of the insertible portion C is a stud which preferably consists of a stem E suitably secured in place and provided with a head F. When inserting the portion C into the section the stud is guided into the notch D which holds said portion laterally, or farther into the section.

G is an aperture in the opposite end of the section and G' is an aperture in the portion C which register with one another when the stud E, F is in its seat. A securing device such as a bolt G², for example, may be used to permanently secure the portion C in place. 70

Since my invention is adapted for use with a removable part for the bottom of a grain spout or a spout for like use where the part lies within the spout it is important that some means of positively holding such part 75 must be employed. That is to say, the friction of the material and the "cast" of such material upon the part tends to loosen it or move it, or any jarring that would tend to displace said part and allow leakage must 80 be prevented. At the same time the means for securing the part must be simple but effective. All this has been provided for in my invention.

Changes in the structure may be made 85 without departing from the inventive idea since it is not my intention to confine myself to the particular arrangement shown and described herein.

Having thus described my invention, I 90 claim:-

1. The combination with a spout section having an opening in its lowermost wall, a removable closure lying within the section covering said opening, one of the portions 95 having a notch at one end, a stud in the adjacent end of the other of the portions adapted to engage to prevent lateral displacement of the closure, and means extending through the other end of the closure and 100 the section for preventing lateral displacement of the closure at that end.

2. The combination with a conical pipe section having an opening in its lowermost

2
wall, a closure within said section tapered to fit the same adapted to lie snugly upon the same closing the opening and adapted for receiving thereon the material being conducted, a notch in the section at one end communicating with the opening, a stud on the narrow end of the closure to engage in the notch preventing lateral displacement of said closure, and means extending through

the other end of the section and closure for 10 preventing lateral displacement of that member at that end.

In testimony whereof I affix my signature, in presence of two witnesses.

RALPH D. WHITMORE.
